(No Model.)

C. A. SPRAGUE.
SASH HOLDER.

No. 331,660.

Patented Dec. 1, 1885.

UNITED STATES PATENT OFFICE.

CHARLES A. SPRAGUE, OF MINNEAPOLIS, MINNESOTA.

SASH-HOLDER.

SPECIFICATION forming part of Letters Patent No. 331,660, dated December 1, 1885.

Application filed August 18, 1885. Serial No. 174,739. (No model.)

To all whom it may concern:

Be it known that I, CHARLES A. SPRAGUE, a citizen of the United States, residing at Minneapolis, in the county of Hennepin and State of Minnesota, have invented a new and useful Improvement in Sash-Locks, of which the following is a specification, reference being had to the accompanying drawings.

My invention has relation to improvements in sash-locks; and the novelty consists of the peculiar construction, combination, arrangement, and adaptation of the various parts for service, substantially as hereinafter fully set forth, and particularly pointed out in the claims.

Among other things, my invention has for its object to provide a sash-lock which shall be capable of application to either sash of the window, to hold the same at any desired adjustment; to obviate the use of cords and weights; to hold the sash against up or down movement when so adjusted, and to provide means which shall combine strength, simplicity, and durability of construction with cheapness of manufacture, and effective and certain in action.

I have shown an embodiment of my invention in the accompanying drawings, referring to which—

Figure 1 represents a perspective view of a portion of a window-frame, showing the sash in dotted lines. Fig. 2 is a detail perspective view of the lock detached from the window-frame. Fig. 3 is a rear elevation of the lock in position in the frame. Fig. 4 is a vertical sectional view on the line $x-x$ of Fig. 3, and Figs. 5 and 6 are detail views of parts of my invention detached from the lock.

Referring to the drawings, in which like letters of reference indicate corresponding parts in all the figures, A designates a window-frame of ordinary well-known construction, and B the sash of the design at present in use, a portion only of said frame and sash being shown herein, inasmuch as the invention will be readily understood by those skilled in the art. At suitable points in the frame A are provided recesses or cut-away portions C, opposite the upper and lower sashes, and in said recessed or cut-away portions I provide or locate one of my improved locks, D, adapt-

ed to act on said sash in juxtaposition thereto, and adapted to hold the same against movement when the sash has been adjusted vertically, or up or down. The locks D are each of 55 substantially the same construction, and I will now proceed to describe the same more fully by letter in the drawings.

E designates the base or supporting plate, on which the several parts are arranged or 60 connected, and which is located in the recessed portions of the frame A, said plate having arms $a-a$, provided with apertures or openings a' , through which are passed screws or bolts b , to secure the plate in position in recessed 65 portions of said frame, as clearly shown. The outer vertical face of the plate E is recessed or cut away, as at c , and in said recessed portion c is arranged a cam-plate, F, said plate being pivoted on a pin or stud, d , to said plate 70 E, and having three outwardly-projecting arms, $F-F'-F''$, arranged at different angles to each other, and cast or formed integral with said plate, as shown. The plate E is provided with a rearwardly-extending solid portion, e , which 75 is arranged at middle of the rear surface thereof, a short distance from the ends, to leave the projecting arms $a-a$, and on the rear surface of said solid portion e , at each side of the plate E, are provided rearwardly-projecting lugs or 80 flanges $f-f$, one arranged to project at each end of said plate, and in a direction opposite to each other, the rear ends of said lugs meeting on lines drawn beyond the middle of the plate E. 85

G G' designate dogs or catches arranged on opposite sides of the plate E, and at opposite ends thereof, said dogs lying parallel with the vertical outer faces of the lugs f and outer edges of the plate E, and pivoted eccentrically 90 to said lugs at their inner reduced or contracted ends, on a common pin or shaft, g , bearing in said lugs and passing through perforations in said dogs, which are loosely mounted thereon and are adapted to freely 95 move or oscillate when acted upon by the cam-arms of the plate F, as will be presently fully described. The outer faces of said dogs G G' are broadened or made wide, and corrugated, roughened, or serrated, as at g' , thus enabling 100 them to take a firm and secure bearing or hold in the sash B. The arm F' of the plate F

bears against the dog G at the rear end of the broadened bearing-surface thereof, which at this point is made plain or smooth; and the arm F² of said plate, which is made somewhat longer than the arm F', bears against the dog G' in a similar manner. When the cam plate F is turned or oscillated by means which I will presently describe, the arms F' F² are turned simultaneously with the plate and in opposite directions, thus forcing the dogs G G' downwardly out of contact with the sash, and simultaneously.

The dogs G G' are kept normally pressed outward, and in contact with the arms of the plate and sash, by means of a spring, H, which is coiled or wound upon the common pivot-shaft of the eccentric dogs g, as at h, and is provided with arms h', which extend in opposite directions on opposite sides of the plate, 20 and having a hook, h², bent or formed on the outer ends of said arms and engaging one of the pivoted dogs G G'.

I designates an operating-lever having a flange, i, cast therewith, and a pivot-lug, i', also cast therewith, through which lug i' is passed a pin or stud to pivotally secure said lever in position upon a supporting-plate, I', secured by means of screws to the exterior face of the frame A, at some distance from the 30 lock D, as clearly shown.

J designates a rod pivotally connected to an aperture in the flange i of said lever I, and at its opposite end to the arm F³ of the eccentric or cam-plate F. This connecting-rod J passes through a slot or opening formed in the lower under surface of one of the strips or beads, J', which serves as a guide thereto.

In order to connect said rod to the lever, the outer end thereof is bent to form a lip, 40 which is passed through the apertured flange of said lever, and the inner end of said rod is bent, as at j, to bring the same on a plane beneath the arm F³, to which it is pivotally connected, by means of an upturned end thereof, to provide a lip or stud, the plate E being provided with a recessed portion, K, in which the end of the link moves, as is obvious.

It will be observed that the spring H 50 keeps the dogs normally pressed outward in contact with the faces of the sash, thus causing the operating - lever I to assume a substantially vertical position; but when pressure is applied to the outer end of said lever 55 it is forced into a horizontal position, which movement draws upon the connecting - rod and the plate F, said plate being oscillated or turned so as to cause its arms to press the dogs simultaneously away from engagement 60 with the sash and against the action of the spring H, when the sash can be adjusted to any desired position.

When the lever is in a substantially horizontal position, the rod J impinges against 65 the lower end thereof, thus preventing the lever from further movement and locking the same in position.

The operation will be readily understood from the foregoing description, taken in connection with the drawings.

By arranging the pivoted dogs or cams at opposite sides and ends of the supporting-plate a firm and secure bearing for the sash is provided, which will prevent the same from moving either sidewise or laterally and 75 vertically, thus obviating the rattling noise incident upon the use of cords and weights in holding a sash, and by the arrangement of said dogs the strain is exerted on the supporting - plate at the enlarged strengthened 80 portion thereof.

Various changes in the form and proportion of parts and details of construction may be made without departing from the principle or sacrificing the advantages of my invention, 85 the essential features of which will be readily understood from the foregoing description, taken in connection with the drawings.

My improved sash - lock is very simple, strong, and durable in its construction, thoroughly effective and automatic in operation, 90 can be quickly and readily applied to window - frames as ordinarily constructed, and cheap and easy of manufacture.

The link for connecting the cam-plate and 95 the operating-lever in the lock for the upper sash is made longer, and in the form shown in Fig. 6 of the drawings, than the link for the lower sash-lock, owing to the distance from said upper sash to the point where it is necessary to locate the operating - lever on the window-frame.

Having thus fully described my invention, what I claim as new, and desire to secure by Letters Patent, is—

1. In a sash-lock, the combination, with a window-frame, of a supporting-plate mounted in said frame, holding-dogs pivoted to said plate, springs secured to the plate for actuating said dogs, a cam - plate pivoted to the 110 supporting-plate and having arms arranged to bear on the dogs, a lever pivoted to the window-frame, and a link connecting said lever and the cam-plate, as set forth.

2. The combination, with a recessed supporting-plate having rearwardly - extending arms, of dogs G, pivoted on a common pin or shaft mounted in said arms, a coiled spring arranged on said shaft and having bent arms adapted to bear on the pivoted dogs, a cam-plate pivoted to the supporting-plate, and a lever pivoted to the window-frame and connected to the cam-plate, substantially as described.

In testimony that I claim the foregoing as 125 my own I have hereto affixed my signature in presence of two witnesses.

CHARLES A. SPRAGUE.
